UNITED STATES PATENT OFFICE

130,974

DESIGN FOR A SWIMMING SUIT

Margit Fellegi Laszlo, Los Angeles, Calif., assignor to Cole of California, Los Angeles, Calif., a corporation of California

Application October 13, 1941, Serial No. 103,754

Term of patent 7 years

To all whom it may concern:

Be it known that I, Margit Fellegi Laszlo, a citizen of the United States of America and residing at 2615 Fruitland Rd., in the county of Los Angeles and State of California, have invented a new, original, and ornamental Design for a Swimming Suit, of which the following is a specification, reference being had to the accompanying drawing forming part thereof.

Fig. 1 is a front perspective view of a swimming suit showing my new design with the skirt portion partly cut away to show the pants.

Fig. 2 is a rear perspective view of the swimming suit as shown in Fig. 1, and

Fig. 3 is a rear perspective view of the swimming suit shown in Fig. 1 with the straps attached to the bodice, instead of being tied as a halter.

I claim:

The ornamental design for a swimming suit, as shown.

MARGIT FELLEGI LASZLO.
